UNITED STATES PATENT OFFICE.

DAVID S. HENNEY, OF NEWARK, NEW JERSEY.

ozonizer.

974,789.

Specification of Letters Patent. Patented Nov. 8, 1910.

Application filed August 1, 1910. Serial No. 574,799.

To all whom it may concern:

Be it known that I, DAVID S. HENNEY, a citizen of the United States, residing at Newark, in the county of Essex and State of New Jersey, have invented certain new and useful Improvements in Ozonizers, of which the following is a clear, full, and exact description.

The object of this invention is to provide an improved device for the production of ozone from the atmosphere, whereby a simple, efficient and economical device may be produced for general hospital and other use.

A further object is to provide a device which is readily attachable and detachable in place.

In carrying out my invention, I make use of a double wall device formed of similar glass cylinders perforated with holes near their ends, and between the holes and the end of each cylinder, the cylinder is reduced in diameter. One of the cylinders is smaller than the other, and shorter, and is inserted in reverse position into the larger, the end being plugged to prevent egress of air, and an electrode suspended within the smaller cylinder. The two cylinders are prepared as in the usual manner with a foil coating, the smaller cylinder having the foil 25 on the inside wall; the larger cylinder has the foil on the outside. The foil on the outside cylinder is connected with one pole of the high potential alternating current, while the electrode within the smaller cylinder is 30 connected with the other pole. In order to make the device easily attachable and detachable, I provide a threaded bushing at the reduced diameter of the outer cylinder, that it may be threaded into place in a 35 socket of similar construction, and I provide a metallic button connected with the electrode, which may be contacted with by a spring-pressed contact block, such contact block being adapted to be lifted upon a rotation of the ozonizer in its socket.

The scope of my invention will be pointed out in the claims.

In the accompanying drawings, Figure 1 is a vertical central cross section of my improved device, taken on line 1-1, Fig. 2. Fig. 2 is a horizontal sectional plan taken on line 2-2, Fig. 1. Fig. 3 is a view on reduced scales, showing outside side elevation of my improved device connected with a blower.

As shown in the drawings, a socket 1 of

insulating material, preferably porcelain, is provided with an interior metallic threaded shell 2, to which is connected one pole 3 of a high potential circuit of alternating current. A pipe 4 connected to the centrally open socket leads to a blower 5, which supplies air to the device for purposes well known and understood in this art. The other terminal or pole 6 leads to a bar 7, in which is slidably mounted a rod 8, having a contact block 9 at one end, the contact block held in the position of Fig. 1 normally by a spiral spring 10 surrounding the rod 8. A pin 11 may be supplied to prevent the rod 70 from leaving the bar 7 when no ozonizing device is in place.

The ozonizer itself consists of a double wall device made up of two similar cylinders, each having a reduced end portion, and each provided with holes in its wall. The outer vessel or cylinder 12, preferably of glass, is provided with a reduced end portion 13, to which there is secured by suitable cement 14 a threaded shell 15 adapted to engage the shell 2 in the socket 1. A strip of copper 16 is secured to the shell 14, and is passed from the reduced portion of the cylinder 12 to a short distance above the corner joining the cylinder proper with the reduced portion. A layer of tin foil 17 is then secured around the major part of the cylinder 16 in contact with the copper strip 16. Around the base of the larger cylinder 17 are a number of apertures or holes 18 for a purpose hereinafter described. The cylinder 19 of glass is formed with reduced portion 20, which is inverted in position with its lower edges in contact with the glass of the outer cylinders at one end, and is provided with holes 21 near its upper end. Tin foil is secured to the inside of this cylinder, as shown at 22. A terminal 23 in the form of a wire provided with brush members 24 in contact with the tin foil, is suspended from an insulating plug 25 secured in the reduced portion of the inner cylinder, and connected to a contact button 26 outside thereof. An annular plug 27 closes the space between the two vessels at their top. The blower 5 directs air through the neck of the outer vessel, the air passing upwardly and through the holes 21 in the wall of such vessel, then down between the walls of the two vessels and out the holes 18 at the base of the outer vessel. I am thus enabled to keep all surfaces cool by the air

blast, thus securing ozone in the improved manner known to the art without danger of puncturing the walls. It will be apparent that by the mere insertion of the ozonizer 5 by a threading motion into the socket, and permitting the spring 10 to depress the contact block 9, that the apparatus can thus be readily attached, and detached, to the poles.

I claim as my invention:

- 10 1. The herein described apparatus for the production of ozone, consisting of an outer cylinder, and an inner cylinder, the outer cylinder having one end of reduced diameter, the inner cylinder resting with its open end in contact with the outer cylinder, means for sealing the two cylinders at one end, both cylinders being open for the ingress of air at the other end, openings in the inner cylinder communicating therefrom to the 15 interior of the outer cylinder, openings from the outer cylinder communicating with the outer air and means for securing an electrical discharge within the device.
- 20 2. The herein described apparatus for the production of ozone, consisting of an outer cylinder, and an inner cylinder, each cylinder having one end of reduced diameter, the inner cylinder resting with its open end in contact with the outer cylinder, means for 25 sealing the two cylinders at one end, both cylinders being open for the ingress of air

at the other end, openings in the inner cylinder communicating therefrom to the interior of the outer cylinder, openings from the outer cylinder communicating with the outer air, such openings being at opposite ends of the apparatus, and means for securing an electrical discharge within the device, the outer cylinder being provided with a base adapted to contact with a receptacle in combination with a receptacle to receive said base.

3. The herein described apparatus for the production of ozone, comprising two similarly shaped open-end glass cylinders of 45 different diameters, each cylinder provided with openings in its wall near one end, each cylinder provided with a layer of foil, one of said cylinders being of a less size than the other and occupying an inverted position 50 with relation to the other, the smaller within the larger, means for closing one end of the device, means for admitting air to the other end of the device, and an electrode within the inner vessel.

Signed at New York city, New York, this 29th day of July 1910.

DAVID S. HENNEY.
